UNITED STATES PATENT OFFICE.

ARCHIE A. KINION, OF SAND SPRINGS, OKLAHOMA.

COLLAR-FASTENING.

1,240,857

Specification of Letters Patent. Patented Sept. 25, 1917.

Application filed September 18, 1916. Serial No. 120,745.

To all whom it may concern:

Be it known that I, ARCHIE A. KINION, a citizen of the United States, residing at Sand Springs, in the county of Tulsa and 5 State of Oklahoma, have invented certain new and useful Improvements in Collar-Fastenings, of which the following is a specification.

This invention contemplates an improved 10 collar fastening and has as its primary object to provide an arrangement wherein the front of the collar may be connected to the neck band of a shirt without the use of the commonly employed collar button, and the 15 invention has as a further object to provide a fastener for the front of the collar including an elastic strip connected with the collar and having a stud secured thereto for engagement through the adjacent button 20 holes of the collar with the said strip adapted to tension the said stud within the said buttonholes.

Other and incidental objects will appear as the description proceeds and in the drawings wherein I have illustrated the preferred embodiment of the invention and wherein similar reference characters designate corresponding parts throughout the several views:

25 Fig. 1 is a perspective view showing a collar equipped at the front with my improved fastener and also illustrating the use of a back fastener for the collar, this latter fastener, however, forming no part of the 30 present invention, and

35 Fig. 2 is a fragmentary sectional view particularly showing the mounting of the fastener at the front of the collar and the manner in which the said fastener is adapted 40 for engagement with the neck-band of a shirt.

Referring more particularly to the drawing, I have illustrated a turnover or roll collar 10 having an inner flap 11 and an 45 outer flap 12. At one end, the inner flap is provided with a short flap 13 in which is formed a buttonhole 14 while at the opposite end of the collar, the said inner flap is formed with a relatively long flap 15 50 adapted to overlie the flap 13 and provided with a buttonhole 16 to register with the buttonhole 14. Formed in the inner flap 11 of the collar, at the rear side thereof, is the usual buttonhole 17 in which may be mount-

ed a fastener 25, this fastener, however, forming no part of the present invention.

Mounted upon the inner flap 11 of the collar, adjacent the inner terminal of the flap 13 is my improved fastener including an elastic strip or other suitable resilient element 18 connected at its upper extremity to the inner face of the said inner flap adjacent the upper edge thereof with the free extremity of the said strip inclined downwardly in the direction of the buttonhole 14 and terminating opposite the said buttonhole. Suitably connected to the free end of the strip 18 is a stud 19 of approved type and in Fig. 2 of the drawings, I have shown the manner in which the said stud is adapted 65 for engagement with the neck band of a shirt for connecting the front of the collar therewith. The overlapping front ends of the neck band of the shirt are indicated at 20 and it will now be observed that the 70 strip 18 is adapted to extend over the said neck band to support the stud 19 in position to extend through the registering buttonholes in the ends 20 of the neck band and through the registering buttonholes of the 75 flaps 13 and 15 of the collar for securely connecting the front of the collar with the shirt. This provides an arrangement eliminating the use of the commonly employed collar button, while, at the same time, the front of 80 the collar may be easily and quickly connected to the shirt. Moreover, attention is directed to the fact that the strip 18 is arranged to normally yieldably pull upwardly 85 upon the inner extremity of the stud 19 and thus tend to tilt the said stud longitudinally 90 within the registering buttonholes of the ends of the neck band of the shirt as well as the buttonholes of the flaps of the collar to consequently bind the said stud within 95 the said buttonholes so that the collar will not likely become unfastened.

Having thus described the invention, what is claimed as new is:

1. The combination with a collar, of a 100 fastener therefor including an elastic strip connected with the collar, and a stud carried by said strip and arranged to extend through a buttonhole in the collar for engagement with a shirt.

2. The combination with a collar having overlapping flaps at its forward side provided with buttonholes adapted to be 105

brought into register, of a fastener for the collar including an elastic strip connected to the inner side of the collar, and a stud carried by said strip and arranged to extend 5 through the registering buttonholes of a neck band of a shirt and through the registering buttonholes of the flaps of the collar

for connecting the collar with the shirt with the said strip normally pulling upwardly upon the stud for tilting the stud longitudinally and binding the stud within the said buttonholes. 10

In testimony whereof I affix my signature.
ARCHIE A. KINION. [L.S.]
